(57) CLAIM

The ornamental design for a hat with a pocket, as shown and described.

DESCRIPTION

FIG. 1 is a perspective view of a first embodiment of a hat with a pocket, wherein the hat is pictured right-side out; FIG. 2 is a cross-sectional view of a first embodiment of a hat with a pocket along line 2-2 in FIG. 1;

FIG. 3 is a perspective view of a first embodiment of a hat with a pocket, wherein the hat is pictured inside out; FIG. 4 is a front elevation view thereof;

FIG. 5 is a back elevation view thereof;

FIG. 6 is a left-side elevation view thereof;

FIG. 7 is a right-side elevation view thereof;

FIG. 8 is a top plan view thereof; and,

FIG. 9 is a bottom plan view thereof.

A second embodiment is being claimed that is a mirror image of the views provided for the first embodiment.

The dashed broken lines in the drawings define the bounds of the claimed design and form no part thereof. The dot-dashed broken lines illustrate the environment of the claimed design and form no part thereof.
